UNITED STATES PATENT OFFICE.

WILLIAM H. TICHBORNE, OF NEW CASTLE, PENNSYLVANIA.

IRONING-TABLE.

No. 857,422.

Specification of Letters Patent.

Patented June 18, 1907.

Application filed September 11, 1906. Serial No. 334,121.

To all whom it may concern:

Be it known that I, WILLIAM H. TICHBORNE, a citizen of the United States, and a resident of New Castle, in the county of Lawrence and State of Pennsylvania, have invented a new and Improved Ironing-Board, of which the following is a full, clear, and exact description.

My invention has for its object to provide an ironing board simple in construction, effective in operation and durable in use, and adapted to be attached to tables of various heights, to be removed therefrom, and folded conveniently for storing when not in use. These objects I accomplish by the means illustrated in the accompanying drawings, in which drawings like characters of reference indicate like parts throughout the views, and in which

Figure 1 represents an ironing board embodying my invention and secured to the edge of a table; and Fig. 2 represents a plan view of the under side of a board embodying my invention with the parts folded together.

As illustrated in the drawings, 1 represents an elongated board having an inclined support 2, pivotally connected by means of a hinge pin 2^a with parallel bars 3, secured to the under side of the board, which serve as braces as well as bearings for the upper end of the inclined support 2. The forward ends of the bars 3 are preferably cut away so as to engage and be secured to a transverse cleat 4, attached to the under side of the board 1. The inclined support 2 is arranged in the central longitudinal line of the board 1, so that the board may be evenly balanced and supported on the upper end of said support. A clamp 5 is mounted upon the inclined support 2, and has a sliding engagement thereon so as to enable the support 2 to be inclined to correspond with the height of the table to which the board may be attached and support the board in a horizontal position. The interior dimensions of the clamp 5 are preferably made slightly larger than the outer dimensions of the support 2, so that an upward or outward pull on the lug 5^a formed on the clamp 5 will cause the opposite ends of said clamp to bear against the opposite edges of the inclined support 2 and lock said clamp in position on the inclined support. A connecting rod and brace 6 is freely connected at one end with the lug 5^a formed on

the clamp 5, and at its opposite end with a lug 7^a formed on a clamp 7 provided with journals 7^c having bearings in a transverse cleat 8 secured to the forward end of the board. The body of the clamp 7 extends backward from the journals 7^c and forms a yoke provided in its lower end with a bearing 7^b adapted to clamp the under surface of the projecting edge of the top of a table 9, the transverse cleat 8 forming a wide bearing for the forward end of the board on the top of the table. After the clamp 7 has been secured to the top of a table, the inclined support 2 is adjusted so as to bring the board 1 into a horizontal position, and the clamp 5 is pressed downward on the inclined support 2 until the edges of the clamp 5 grasp the edges of the inclined support firmly and hold said support in the desired position. A sleeve board 10 may be pivotally attached to the board 1 by means of a pivot pin 10^a, and spaced apart from said board by means of a block 11 so as to enable cloth to be wound around said sleeve board, and at the same time enable the sleeve board to be turned under the ironing board 1.

Having thus described my invention, what I claim as new and desire to secure by Letters Patent is:

1. The combination with an ironing board having its end provided with a transverse clamping cleat, of a clamp comprising a yoke pivoted at one end to said cleat and provided on its opposite end with a clamping face, an inclined support hinged to said board, a clamp adjustable lengthwise of said inclined support, and a rod connecting said clamps, substantially as shown and described.

2. The combination with an ironing board, of a clamp comprising a yoke pivoted at one end to said board and provided on its opposite end with a clamping face, an inclined support hinged to said board, a clamp adjustable lengthwise of said inclined support, and means for connecting said yoke and clamp, substantially as shown and described.

In testimony whereof I have signed my name to this specification in the presence of two subscribing witnesses.

WILLIAM H. TICHBORNE.
